CONTROL VALVE

William Wesley Jones, Lincoln, Nebr.

Application May 6, 1936, Serial No. 78,216

6 Claims. (CL. 251—10)

This invention relates especially to well drilling apparatus and has for an object a provision of means for closing the passage through a well casing in the event of a gusher, or of fire, the closing means also serving to shut off the well for any other reason or purpose.

Another object of the invention is to provide for the removal of tools.

With the above and other objects in view, the invention further includes the following novel features and details of construction, to be hereinafter more fully described, illustrated in the accompanying drawings and pointed out in the appended claims.

In the drawings:—

Figure 1 is a vertical sectional view of the valve shown in open position.

Figure 2 is a horizontal sectional view of the valve taken at line —— of Figure 3 showing valve in closed position.

Figure 3 is a vertical sectional view of a portion of the valve showing valve in closed position.

Figure 4 is an elevation of a fixed segment of the inner member of the valve housing taken toward the inner chamber of the valve.

Referring to the drawings in detail wherein like characters of reference denote corresponding parts character 1 represents the outer housing threaded at each end to fit into suitable reducing collar 2—2 said housing enclosing a control housing 3 which in turn encloses inner member 4 to which is attached a plurality of hinged segments 5 so designed that they will coordinate to effect a complete closure when the free ends of the hinged segments 5 are coordinately drawn toward the center of the inner chamber 6 and valve may be opened by drawing the free ends of hinged segments 5 coordinately into spaces 7, or

drawn at any intermediate position desired. The aforementioned operations are effected by opening cable 8 and closing cable 9, both cables are attached to and operated by suitable control shaft 10 operating within operating space 11 in control housing 3.

Opening cable 8 is alternately threaded through apertures 12 in hinged segments 5 and apertures 13 in fixed segments 14 of the inner member 4, both ends of said opening cable 8 are fixedly attached to control shaft 10.

Closing cable 9 is threaded through apertures 15 in hinged segments 5 and both ends of said closing cable 9 are fixedly attached to control shaft 10.

In fixed segments 14 of inner member 4 are

notches 16 for the accommodation of closing cable 9 when valve is in open position and notches 17 for the accommodation of opening cable 8 when valve is in open position.

Suitable set screws 19 are provided to help secure valve housing and inner member.

In order to provide space for opening cable 8 and closing cable 9 when coiled about control shaft 10 an enlarged operating space 18 is provided, also openings 19 and 20 through hinged 10 segment nearest operating shaft are provided respectively for passage of opening cable 8 and closing cable 9.

A detailed description of the operation of my invention follows:

Consider the valve entirely open as shown in Figure 1, the hinged segments 5 fit between fixed segments 14 of inner member 4 of the valve in such manner that inner surfaces of hinged segments 5 are flush with inner surfaces of the 20 inner member 4 and fixed segments 14 thereof and opening cable 8 and closing cable 9 are fully recessed in apertures 12 and 15 and notches 16 and 17. In this position the ends of opening cable 8 are coiled around control shaft 10 in operating space 18 in its extreme open position while the balance of opening cable 8 is fully recessed within apertures 12 in hinged segments 5 and apertures 13 and notches 17 in fixed segments 14 of the inner member 4 and coiled about operating shaft 10. While valve is in said extreme open position, closing cable 9 is fully uncoiled from said control shaft 10 and fully recessed in apertures 15 of hinged segments 5 and notches 16 of fixed segments 14 of inner member 4 said 35 closing cable threaded alternately through apertures 15 of hinged segments 5 and through notches 16 of fixed segments 14 of inner member 4 in a plurality of turns.

Now it will be seen that by rotating control 40 shaft 10 to uncoil opening cable 8 that closing cable 9 will simultaneously be coiled around control shaft 10 in an opposite direction to that of opening cable 8. By this operation the free ends of hinged segments 5 are coordinately drawn 45 toward the center of inner chamber 6 so as to ultimately close the passage therethrough. The valve is now in its closed position.

Referring now to Figure 3 it will be seen that closing cable 9 is coiled to its extreme position 50 about control shaft 10 while opening cable 8 is entirely uncoiled from control shaft 10. It will be seen that by thus drawing opening cable 8 about operating shaft 10 the free ends of hinged segments 5 are drawn into spaces 7 between fixed 55

segments 14 by reason of the fact that said opening cable 8 is alternately threaded through apertures 12 in hinged segments 5 and apertures 13 in fixed segments 14 of the inner member 4. The valve is now in its original open position.

5 A balance in tension of the cables is achieved through the placement of the two cables in relation to each other which balance may be maintained throughout the operations of opening or closing the valve.

10 In open position the inner chamber is entirely unobstructed of valve mechanism permitting normal drilling operations.

Having described the invention what is claimed

15 is:—

1. A casing valve comprising a housing provided with means for connecting housing to casing at either or both ends, a plurality of triangular hinged segments attached interiorly thereto and so designed that the free ends of said segments

20 may be coordinately swung together to form a pyramidal or conic shaped unit to entirely shut off the passage or flow therethrough with suitable mechanical means for bringing the free ends

25 of said hinged segments together.

2. A casing valve comprising a housing constructed to contain recesses within its inner wall provided with means for connecting housing to casing at either or both ends, a plurality of hinged segments attached interiorly thereto and so designed that the free ends of said segments may be coordinately swung together to entirely shut off the passage or flow therethrough and a cable or cables for drawing together said free ends of

30 said hinged segments, said cable operating between the walls of the valve, and in open position of valve, entirely disposed within the recesses of

35 the inner wall so as to leave an unobstructed cylindrical opening through the valve.

40 3. A casing valve comprising a housing provided with means for connecting housing to cas-

ing at either or both ends, a plurality of hinged segments attached interiorly thereto and so designed that the free ends may be coordinately swung together to entirely shut off the passage or flow therethrough, a closing cable slidably attached toward the free ends of said hinged segments in such manner that the free ends may be drawn together to effect a closure of the passage therethrough.

4. A casing valve comprising a housing provided with means for connecting housing to casing at either or both ends, a plurality of hinged segments attached interiorly thereto and so designed that the free ends thereof may be coordinately swung together to entirely shut off the passage or flow therethrough, an opening cable attached to and toward the free ends of said hinged segments and alternately to the housing at points intermediate to location of hinged segments.

10 5. A casing valve comprising a housing provided with means for connecting housing to casing at either or both ends, a plurality of hinged segments attached interiorly thereto and so designed that the free ends thereof may be coordinately swung together to entirely shut off the passage or flow therethrough, and suitable means disposed within housing for coordinate operation of said closing and opening cables.

15 6. A casing valve comprising a housing provided with means for connecting housing to casing at either or both ends, a plurality of triangular hinged segments interiorly attached thereto and so designed that the free ends of said segments may be coordinately swung together to form a pyramidal or conic shaped unit to entirely shut off the passage or flow therethrough, said housing being so designed as to accommodate the whole of said hinged segments within its inner wall when valve is in full open position.

20 30 35 40 WILLIAM WESLEY JONES.
